BREATHING SHOE

Seneca B. Austin, Balboa, C. Z.

Application February 7, 1946, Serial No. 646,088

2 Claims. (Cl. 36—3)

1

The invention as described herein, and illustrated in the accompanying drawings, consists of a shoe sole, an object of which is to provide a detachable insole so formed that it will create a constant circulation of air within and throughout the inside of a shoe.

Another object of the invention is to provide a resilient insole provided with a series of channels intermediate its upper and lower surfaces, the walking operation of a wearer of which will alternately collapse and expand the channels with every step of the wearer to draw in and expel air throughout the shoe.

A primary object of the invention is the provision of means, through the medium of an insertable insole, to prevent perspiring of the feet and especially the toes which normally results in soreness or intense itching.

Other features and advantages will become more readily apparent from the following description and the accompanying illustrative drawings in which:

Fig. 1 is a side elevation of a shoe partially broken away and in section, with the insole disposed therein being shown in longitudinal section.

Figure 2 is a longitudinal, sectional view through the shoe and the forward portion of the removable insole, the heel of said insole being shown in elevation.

Figure 3 is a sectional view on line 3—3 of Figure 2, and

Figure 4 is a similar view on line 4—4 thereof.

While one embodiment of the invention is illustrated in the above referred to drawings, it is to be understood that they are merely for the purpose of illustration and that various changes in construction may be resorted to in the course of manufacture in order that the invention may be utilized to the best advantage according to circumstances which may arise without in any way departing from the spirit and intention of the device which is to be limited only in accordance with the appended claims. And while there is stated the primary field of utility of the invention it remains obvious that it may be employed in any other capacity wherein it may be found applicable.

In the accompanying drawings, and in the following specification, the same reference characters are used to designate the same parts and elements throughout and in which 10 refers to a thin leather casing in which the improved insole is housed.

The insole is formed of rubber or some other

like resilient material of a shape and size to fit into a shoe and the material is transversely split from its toe end 12 to its shank 14. Within the layer 15 of the device is provided a U-shaped channel 16 which extends from the toe portion 12 to said shank, said channel being traversed by a series of arcuate cross channels 17, 18, 19 and 20, which form in the instep portion 21 a series of opposing upper and lower normally spaced apart lugs 22, 23 and ribs 23', etc., which when weight is applied to the surface 24 of the insole the upper lugs will collapse upon the lower lugs compressing both sets and closing the said channels, exhausting all air therefrom and driving it through the apertures 24', in the toe end 25, of channel 16, thus driving the air out, causing its circulation around the toes and foot. Upon lifting the said weight, the expansive ability of the material will cause it to return to its normal state again, enlarging the channels, causing suction to again draw in air from the interior of the shoe, the depletion of which within the shoe causing a fresh supply to be drawn in from the upper edge 26 of the shoe surrounding the ankle 25 of the wearer.

One or more apertures 26' may be provided at or near the instep portion 21 whereby when the foot is lifted in walking air will be drawn into the cavity and upon bearing down the foot will close said opening 26' and the pressure will force the entrapped air out through the apertures 24' and then be forced around the foot.

From the foregoing specification it will become apparent that the invention disclosed will adequately accomplish the functions for which it has been designed and in an economical manner and that its simplicity, accuracy and ease of operation are such as to provide a relatively inexpensive device considering what it will accomplish and that it will find an important place in the art to which it appertains when once placed on the market.

It is thought that persons skilled in the art to which the invention relates will be able to obtain a clear understanding of the invention after considering the description in connection with the drawings. Therefore, a more lengthy description is regarded as unnecessary.

Changes in shape, size and rearrangement of details and parts such as come within the purview of the invention claimed may be resorted to, in actual practice, if desired.

Having now described the invention that which is claimed to be new and desired to be procured by Letters Patent is:

1. In combination with a shoe, of a removable insole therefor including a flexible casing, a resilient rubber filler therein having intersecting transverse and longitudinal interiorly disposed channels adjacent the instep portion thereof providing oppositely disposed similarly shaped vertically spaced lugs, and said insole being formed with an air inlet port through its upper surface connected with one of said transverse channels and with a plurality of outlet ports through its lower surface adjacent the toe end of said insole.

2. A compressible rubber insole having trans-

verse and longitudinal intersecting channels interiorly disposed therein forming opposed vertically spaced lugs, said insole having an air outlet port between said channels and its upper surface adapted to permit air to enter said channels when pressure is removed from the insole, and having air discharge outlet ports between said channels and its lower surface for discharging the air from said channels when said outlet is closed and weight is applied to said insole and the same compressed.
